DIAMOND

George Saltzman, 36 W. 47th St.,
New York, N.Y. 10036

Filed Jan. 18, 1967, Ser. No. 5,469

Term of patent 14 years

(Cl. D45—2)

FIG. 1 is a top plan view of a diamond showing my new design; and

FIG. 2 is an end elevational view looking in the direction of the cleft of the heart shape diamond of FIG. 1. That portion of the base not shown extending from the girdle to the bottom of the jewel is faceted identically to the portion shown.

A characteristic feature of the ornamental design of the invention is the heart shape configuration of the girdle of the jewel, the cleft of such configuration being formed of multiple and contiguous facets.

I claim:

The ornamental design for a diamond, as shown and described.
